UNITED STATES PATENT OFFICE.

HENRY WEIL, OF NEW YORK, N. Y.

DESIGN FOR A PILLOW-COVER.

44,462.

Specification for Design.

Patented Aug. 5, 1913.

Application filed April 25, 1913. Serial No. 763,676. Term of patent 3½ years.

To all whom it may concern:

Be it known that I, HENRY WEIL, a citizen of the United States, residing at New York, in the county of New York and State of New York, have invented a new, original, and ornamental Design for Pillow-Covers, of which the following is a specification, reference being had to the accompanying drawing, forming part thereof.

The figure is a plan view of a pillow cover, showing my new design.

I claim:

The ornamental design for a pillow cover, as shown.

HENRY WEIL.

Witnesses:

THEO. A. HERRING,
ALMA STERN.
